UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed May 9, 1921. Serial No. 467,910.

This invention relates to window control mechanism, and more particularly to controlling means for vertically slidable window members such as are commonly employed on motor vehicles.

It is the object of the invention to provide a control mechanism for a sliding window member which is adapted, in its open position, to enter a chamber adjacent the window opening, which mechanism will be actuatable by a handle slidable transversely of the direction of travel of the window member and which projects from said chamber in all positions of adjustment.

A further object of the invention is to provide a mechanism of the character described that will be irreversible and will require a comparatively slight muscular effort in exercising control.

In the drawings:

Figure 1 is an interior view of a motor vehicle door partially broken away to disclose the control mechanism chambered in said door;

Figure 2 is a similar enlarged view of this mechanism;

Figure 3 is a fragmentary vertical section on line 3—3 of Figure 1 showing the means constraining the actuating handle to rectilinear movement.

Figure 4 is a fragmentary edge view of the driving gear segment.

In these views the reference character A designates a motor vehicle door having in its upper portion the window opening B and provided with a closure for said opening, having the nature of a vertically slidable glass plate C, which in its lowered or opened position is adapted to enter a chamber D formed in the lower portion of the door. Within said chamber a control arm E is pivoted at one extremity upon a bracket F secured to one of the side uprights of the door and carries upon its other end the roller G engaging beneath the plate C. To the pivotal end of said control arm there is secured a segmental bevel gear H with which is enmeshed a driving pinion I upon a shaft I'. Said shaft is journaled in a pair of

bearings I² integrally formed upon an arm J mounted upon the bracket F co-pivotal with the control arm E. Upon its outer end the shaft I' carries a helical pinion K enmeshed with a segmental helical gear L jour-

nalled upon the free end of an upward terminal extension M of the arm J. The gear L is adapted to be rocked by a handle N connected to said gear by a pair of rods O symmetrically disposed at each side of the center line of the gear and handle and extending divergently from the handle to the gear. Upon the handle N is mounted a ball-headed pin P, the head of which is slidably engaged in a sheet metal channel Q formed preferably from a single strip of folded sheet metal and secured between the sill R of the window and the finish strip S of said sill. Said channel strip extends substantially the full width of the window opening and is transversely curved to conform to the shape of the ball head of the pin P, (see Figure 3) embracing said head sufficiently to retain the same from disengagement.

In the operation of the described mechanism, the handle C is constrained to travel in a rectilinear line transverse to the direction of travel of the window member and when thus actuated said handle both rocks the gear L and shifts said gear together with the free end of the arm J bodily upward or downward according to the direction of travel of the handle. Rocking of the segment L rotates the pinion K and shaft I' and rotation of said shaft acts through the gears H and I to rock the control arm E. The pitch of the helical teeth of the pinion K and gear L is such as to provide a lock against a reverse drive, and consequently the sliding window member must remain stationary in any position of adjustment. Figure 1 discloses suitable counterbalancing means for the sliding window member consisting of an arm T pivoted at one end upon the opposite upright to that which carries the bracket F and bearing upwardly at its other end upon the sliding window member, said arm being upwardly urged by the coil spring U.

What I claim as my invention is:

1. In a window control mechanism, the combination with a sliding window member and a chamber receiving said member in the opened position thereof, of a control arm pivotally mounted in said chamber and engaging said window member, an arm within said chamber co-pivotal with said control arm, a shaft journaled upon said arm, gear-

ing actuating the control arm from said shaft, and a rocking element for actuating said shaft journalled upon said arm and provided with a handle projecting from said 5 chamber and constrained to a direction of travel transverse to that of the window member.

2. In a window control mechanism, the combination with a slidable window member 10 and a chamber receiving the same in its opened position, of a control arm pivotally mounted within said chamber and engaging said window member, a rock arm co-pivotal with said control arm, a shaft journalled up- 15 on said rock arm, gearing actuating the control arm from said shaft, a rocker member journalled upon said arm for actuating said shaft and provided with a control handle, a pin mounted upon said handle, and 20 a channel member slidably engaged by said pin and extending at the edge of the window opening adjacent said chamber whereby the handle member is constrained to travel along said edge.

25 3. In a window control mechanism, the combination with a vertically slidable window member, and a chamber receiving said window member in its lowered or opened position, a control arm pivotally mounted 30 within said chamber and engaging said window member, a rock arm within said chamber co-pivotal with said control arm, a shaft journalled upon said rock arm, gearing actuating the control arm from said shaft, a 35 helical pinion upon said shaft, a helical gear journalled upon said arm enmeshing with said pinion, a stationary channel member adjacent the top of said chamber, a handle rigidly secured to said helical gear, and a 40 projection upon said handle engaging in said channel.

4. In a window control mechanism, the combination with a sliding window member, of two co-pivotal arms, one of which has 45 actuating engagement with said window member, a drive connection between said arms effecting a relatively large angular travel of the window engaging arm, as compared to that of the driving arm and an 50 actuating member connected at one end to the driving arm and having its other end restrained to a substantially rectilinear travel transverse to that of the window member.

5. In a window control mechanism, the 55 combination with a sliding window member, of a pivotal control arm engaging said window member, a second arm co-pivotal with said control arm, a shaft journalled upon said second arm, a drive connection to the 60 control arm from said shaft, and an actuating member for said shaft engaging the outer end of the arm carrying the shaft and having a handle portion constrained to a substantially rectilinear travel transverse to that of 65 the window member.

6. In a window control mechanism, the combination with a sliding window member, of a pivotal control arm engaging said member, a shaft having driving engagement at one extremity with said control arm and bodily angularly actuatable about the axis of 70 said arm, and an actuating element having driving engagement with the other extremity of said shaft and having a handle portion constrained to travel in a direction substantially transverse to that of the window member. 75

7. In a window control mechanism, the combination with a sliding window member, of a pivotal control arm therefor, a shaft having driving engagement at one end with 80 said control arm, and a rocking element having a drive connection with said shaft and having a handle constrained to travel in a direction substantially transverse to that of 85 the window member.

8. In a window control mechanism, the combination with a sliding window member, of a pivotal control arm for said member, an actuating element having a handle portion constrained to travel in a rectilinear direction substantially transverse to that of the window member, a drive connection from the actuating element to said arm including a 90 rotatable element, and a unitary mounting 95 for said arm, actuating element, and drive connection.

9. In a window control mechanism, the combination with a sliding window member, of two co-pivotal arms, one of which has 100 actuating engagement with said window member, a drive connection between said arms effecting a relatively large angular travel of the window engaging arm as compared to that of the driving arm, and an 105 actuating element for the driving arm engaging the free end thereof.

10. In a window control mechanism, the combination with a sliding window member, of a pivotal control arm engaging said window member, a second arm co-pivotal with 110 said control arm, a shaft journalled upon said second arm, a drive connection to the control arm from said shaft, and an actuating member for said shaft engaging the outer end of the shaft carrying arm. 115

11. In a window control mechanism, the combination with a sliding window member, of a pivotal control arm engaging said member, a shaft having driving engagement 120 at one extremity with said control arm and bodily angularly engageable about the axis of said arm, and a swinging actuating element for said shaft, and a drive connection between said swinging element and the outer end of the shaft. 125

12. In a window control mechanism, the combination with a sliding window member, of a pivotal control arm for said member, a swinging actuating lever having a 130

- handle constrained to travel in a direction substantially transverse to that of said window member, a mounting for said lever pivotal with said control arm, and a drive connection from said lever to the control arm.
13. In a window control mechanism, the combination with a sliding window member, of a pivotal control arm for said member, a swinging actuating lever having a handle constrained to travel in a direction substantially transverse to that of the window member, a mounting for said lever pivotal with the control arm, and a rotative element forming a drive connection from said lever to said arm journaled upon said mounting.
14. The combination with a vertically sliding window member, and a chamber receiving said member in its lowered position, a control arm fulcrumed within said chamber, a shaft for actuating said arm, said shaft being bodily angularly actuatable about the fulcrum of said arm, a unitary mounting for said arm and shaft, and actuating means for said shaft.
15. In a window control mechanism, the combination with a vertically sliding window member, and a chamber receiving said member in its lowered positions, of an actuating unit for said window member disposed within said chamber and comprising a fulcrumed control arm, a drive shaft for said arm, a support for said drive shaft, means for angularly actuating the arm from said shaft, a common mounting for said
- arm, and support, and a member mounted upon said support for actuating said shaft.
16. In a window control mechanism, the combination with a vertically sliding window member, and a chamber receiving said member in its lowered positions, an actuating unit for said member disposed within said chamber and comprising a fulcrumed control arm, a drive shaft, speed reducing mechanism angularly actuating the arm from the shaft, the axes of rotation of the arm and shaft being transverse, a member for actuating the shaft, and a unitary mounting within said chamber for said arm, shaft speed reducing mechanism and shaft actuating member.
17. In a window control mechanism, the combination with a member formed with a window opening, a vertically sliding window member forming a closure for said opening, and a chamber receiving said member in its lowered positions, a unitary mechanism within said chamber comprising a mounting, a control arm fulcrumed upon said mounting, a drive shaft for said arm having its axis transverse to the axis of angular movement of the control arm, a support for said drive shaft bodily angularly actuatable about the fulcrum of said arm, a drive connection from said shaft to said arm, and an actuating handle for said shaft adjacent said window opening.

In testimony whereof I affix my signature.

STANLEY W. NICHOLSON.
